AUTOMOTIVE TAIL LAMP

Richard A. Teague, Rochester, Mich., assignor to Stude-baker-Packard Corporation, a corporation of Michigan

Application October 8, 1954, Serial No. 32,601

Term of patent 14 years

(Cl. D48—32)

Figure 1 is a perspective view of my novel design for an automotive tail lamp;

Figure 2 is a side elevational view of the design of Figure 1;

Figure 3 is a face view in elevation of the design of Figure 1; and

Figure 4 is a sectional view on the section lines 4—4 of Figure 3.

While the fragmentary dotted line outline of associated parts of an automobile are shown only for purpose of illustration in Figures 1 and 2, the dominant feature of my design resides in the full line portion of the drawing.

I claim:

The ornamental design for an automotive tail lamp, substantially as shown and described.
